UNITED STATES PATENT OFFICE.

JOHN B. OLDERSHAW, OF BALTIMORE, MARYLAND.

HEATING-STOVE.

SPECIFICATION forming part of Letters Patent No. 268,718, dated December 5, 1882.

Application filed August 14, 1882. (No model.)

To all whom it may concern:

Be it known that I, JOHN B. OLDERSHAW, of the city of Baltimore, in the State of Maryland, have invented certain Improvements in Stoves, of which the following is a specification.

The object of this invention is to increase the heating capacity of a stove and to equalize the temperature in all parts of the room in which the stove is situated.

In carrying out my invention, as hereinafter fully described, I provide the stove with an air-duct having its inlet end near the bottom of the stove and its outlet end terminating in a hot-air chamber covered by a perforated plate situated over the magazine. The coldest stratum of air in the room, which is necessarily on the floor, enters the air-duct, becomes heated, passes to the hot-air chamber, and thence through the perforated cap-plate again to the room. By this means the hot air in the room is gradually depressed to take the place of the colder body which rises through the duct, as described. The result of this circulating movement of air is the gradual equalization of temperature of the whole body of air in the apartment.

In the further description of my invention which follows, reference is made to the accompanying drawings, forming a part hereof, and in which—

Figures I and II are respectively an exterior and a sectional view of the improved stove, looking from the same point. Fig. III is a top view of Fig. I; and Fig. IV is a section of Fig. II, taken on the dotted line *x y*.

Similar letters of reference indicate similar parts in all the views.

A is the casing of the stove, and B is the grate.

C is the fire-chamber, and D the ash-receptacle, in which the ash-pan *a* is situated.

E is the magazine, having a feed-opening, *b*, and *c* is the exterior feed-door in the casing of the stove, opposite to the opening *b*. The top of the magazine has a small aperture, *d*, for the escape of gases to the fire-chamber C.

F is the hot-air chamber, which is considerably less in diameter than the upper section of

the casing A, in order to form an annular space, *e*, from which the stove-pipe *f* extends. 50 The hot-air chamber is surmounted by an ornamental perforated cap-plate, G, through which heated air escapes to the room.

The air-duct is represented by H, and it may be formed either by part of the casing A, as shown in the drawings, or by an independent pipe. 55 In either case it discharges air to the interior of the hot-air chamber, as shown in the drawings.

In Fig. II the direction of movement of the 60 gases and other products of combustion is indicated by arrows in broken lines, and that of the air by arrows in full lines.

The stove is provided with the usual doors and other necessary devices; but these are of 65 ordinary design and need no special description herein.

It will be seen that the heated gases and smoke, in their passage to the annular space around the hot-air chamber, strike against the 70 under side or bottom of the said chamber, and the air therein is thereby heated to some extent independently of the hot-air duct. By this means a more rapid movement of air is effected than if the circulation were caused by 75 rarefaction in the duct alone.

I claim as my invention—

In a stove, the combination of a fire-chamber, a magazine situated within the said fire-chamber, with a space around and over it for 80 the exit of gases and other products of combustion, a hot-air chamber or reservoir suspended over the said magazine and separated by a space from it, and having an annular enclosed space around it, into which the said 85 gases are delivered before being discharged to the smoke-pipe, and provided with a perforated cover and a duct or pipe to carry air from near the bottom of the stove to the lower part of the said hot-air chamber, substantially as and 90 for the purpose specified.

JOHN B. OLDERSHAW.
